CLAIM

The ornamental design for an actuator, as shown and described.

DESCRIPTION

Fig. 1.1 is a perspective view of an actuator;

Fig. 1.2 its front view;

Fig. 1.3 its right side view;

Fig. 1.4 its left side view;

Fig. 1.5 its top view;

Fig. 1.6 its rear view; and

Fig. 1.7 its bottom view.

The broken lines in the drawings illustrate portions of the actuator which form no part of the claimed design.
